UNITED STATES PATENT OFFICE.

CHARLES U. CARPENTER, OF NEW YORK, N. Y., ASSIGNOR TO DAYTON PORTABLE TYPEWRITER COMPANY, OF DAYTON, OHIO, A CORPORATION OF DELAWARE.

TYPEWRITING MACHINE.

Application filed December 1, 1921. Serial No. 519,263.

To all whom it may concern:

Be it known that I, CHARLES U. CARPENTER, a citizen of the United States, residing at New York city, in the county of New York and State of New York, have invented certain new and useful Improvements in Type-writing Machines, of which the following is a specification.

My invention relates to typewriting machines, and has for its object the provision of means whereby a continuously accelerated movement is imparted to the type-carrying element throughout the printing stroke thereof; and further, the provision of novel means whereby the type-carrying element is retracted with an initially quick movement so as to quickly clear the type-impressing space at the platen between printing strokes of successive type-carrying elements having 20 converging printing paths.

It is the object of my invention further to provide novel means whereby the printing stroke of a type-bar is initiated with a comparatively slow movement, and this movement continuously accelerated throughout the progress of the printing stroke so that the printing impact upon the ribbon is effected when the type-bar has attained its greatest velocity and consequently its greatest force; and further, to provide novel means whereby a light touch of the finger will initiate the printing stroke of the type-bar and cause its acceleration, the type-bar gathering momentum during the printing 35 stroke; and the inertia of motion of the type-bar aiding in completing the printing stroke.

It is the object of my invention further to provide a novel typewriter of the portable type; to provide novel means in a typewriter of this type whereby excellent work is produced with little effort; whereby the printing is accomplished by novel means employing few parts which are strong and durable and readily assembled; and to provide novel parts and arrangements and combinations of parts which can be produced at low cost.

The invention will be further readily understood from the following description and claims, and from the drawings, in which latter:

Fig. 1 is a diagrammatic representation of the principle of operation of embodiments 55 of my invention.

Fig. 2 is a side elevation of an embodiment of my invention.

Fig. 3 is a cross-section of a portion of the same, taken on the line 3—3 of Fig. 2.

Fig. 4 is a side elevation of another embodiment of my invention.

Fig. 5 is a side elevation of a further embodiment of my invention.

Fig. 6 is a cross-section of a portion of the same, taken on the line 6—6 of Fig. 5.

Fig. 7 is a side elevation of another embodiment of my invention.

Fig. 8 is a cross-section of a portion of the same, taken on the line 8—8 of Fig. 7.

Fig. 9 is a side elevation of another embodiment of my invention.

Fig. 10 is a side elevation of a still further embodiment of my invention.

Fig. 11 is a cross-section of the same, taken on the line 11—11 of Fig. 10.

Fig. 12 is a side elevation of another embodiment of my invention; and,

Fig. 13 is a side elevation of a further embodiment of my invention.

I have in Figs. 2, 4, 5, 7, 9, 10, 12 and 13 shown the operative parts in retracted or normal position in full lines and in printing position in dotted lines, so much of the frame of the typewriter as is necessary to illustrate my invention being shown in cross-section, and it being assumed that the printing action forces the ribbon upon the sheet or sheets being printed backed by the tympan roller.

Explaining the principle of operation of embodiments of my invention for obtaining continuously accelerated movement of the type-carrier throughout the printing stroke, and referring to Fig. 1, it will be assumed that the lines 21, 22, represent the pair of links of a toggle 23, articulated together at 24, that 25 represents a stationary pivot for one end of the toggle, and that the line 26, which also represents the upper position of the links, represents the linear path of movement of the type-bar, the other end of the toggle being articulated at 27 with the type-bar so as to move in said path.

Swinging of the link 21 on its pivot 25 causes its articulation 24 to describe the arc represented by the dotted line 28. It will be assumed that the link is swing in equal steps, represented by the positions 31, 32, 33, 34, 35, 36 and 37 of the articulation 24. Such swinging of the link 21 in steps

of equal distances causes movement of the articulation 27 along the path 26 of the type-bar continuously increasing distances represented by the steps 41, 42, 43, 44, 45, 46 and 5 47, whereby the swinging of the link 21 at regular speed causes movement of the articulation 27 at continuously increasing speed, resulting in continuous acceleration 10 of movement of the articulation 27 throughout its movement.

Upon return of the articulation 27 to its normal position along the path 26, the reverse relation of speeds obtains, the initial portion of the return movement of the articulation 27, and of the type-bar to which it is articulated, taking place at primarily rapid speed, to clear the printing space adjacent to tympan or roller quickly by the type-bar which has just completed its printing stroke for the reception of the next following type-bar which is to print in said printing space, when employing paths of type-bars which converge to a common printing point at the tympan roller.

25 Referring now to Figs. 2 and 3, the frame of the typewriter is represented at 51, a tympan roller at 52 and a ribbon at 53. A type-carrier, shown as a slidable type-bar 54, has a suitable number of type 55, 56 and 30 57 thereon. Suitable means are provided to raise and lower the tympan roller and ribbon for placing their impression portions opposite the type on the type-bar which is to print upon a suitable sheet of paper or 35 duplicating sheets received about the roller between the roller and ribbon in any ordinary or usual manner.

A key-lever 61 is pivoted on an arcuate cross-rod 62 to the frame of the machine and 40 has a key 63 thereon. The type-bar is guided preferably in a right-line path toward and from the roller, as by being received in guide-slots 64, 65, of arcuate guide-plates 66, 67, suitably secured to the frame, the 45 paths of the collective type-bars converging toward a common printing point at the roller.

The converging relations of neighboring key-bars is indicated in Fig. 3, in which 50 three key-bars and associate mechanisms are shown, the middle one of which is a true end-view, and the side ones of which show parts of the sides of the type-bars and key-levers presented towards said middle type-bar and key-lever.

A toggle 68 comprises links 69, 70, articulated together by an articulation 71. The link 70 has movement in a slot 72 in the plate 67. One end of the toggle is pivoted 60 by means of a pivot 73 to a stationary part of the frame of the machine. The other end of the toggle has articulation 74 with the type-bar. A link 75 has articulation with the articulation 71 at the knee of the toggle, 65 and articulation 76 with the key-lever. The

links of the toggle are normally located in extended relation so that the toggle extends in the general direction of the path of the type-bar with which it is connected. Each of the type-bars has its own toggle mechanism connected thereto, all of which are 70 duplicates of each other.

When the key-end of the key-lever is depressed, the knee of the toggle is also depressed, whereby the swinging end of the link 70 moves downwardly on an arc to correspond with the arc 28 of the diagram in Fig. 1, thereby moving the type-bar in printing direction with a continuously accelerating movement which is complemented by the 80 inertia of motion of the type-bar for imparting a quick, sharp printing blow to the ribbon and roller, and immediately returning to normal position, as explained with reference to the principle of operation and diagram shown in Fig. 1.

The swinging movement represents equal distances of the knee of the toggle and results in movements of continuously increasing distances of the type-bar, for imparting the desired momentum and force of stroke thereto. When the type-bar is in striking position, it and the lengths of the toggle form a substantial triangle, as indicated in dotted lines in Fig. 2, representing the actuated or printing position of the elements.

The key-lever is retracted to normal position by means of a spring 77, connected respectively to the key-lever and a stationary part of the frame, and the return of the key-lever may be aided by a light spring 78, having connections at its respective ends with the link 70 and a stationary part of the frame. A cushion-pad 79 for cushioning the 100 return of the lever may be provided.

The initial portion of the return stroke of the type-bar takes place with rapid motion to quickly clear the printing space adjacent to the roller 52 for the reception of the next type-bar actuated, as explained with 105 reference to the diagram in Fig. 1.

In the embodiment of my invention exemplified in Fig. 4, similar parts are shown and designated by similar reference numerals 110 with the exponent prime ('). In this exemplification the link 75' has articulation at 81 with the link 69' at a point intermediate of the ends of link 69', and said link 75' has the articulation 76' with the key-lever closer to the pivot of the key-lever than in the exemplification shown in Fig. 2, whereby the power exerted upon the toggle is increased and the stroke of the key-end of the key-lever is diminished.

Initial return of the type-bar is effected at 115 a comparatively quick speed as explained with reference to the embodiment shown in Figs. 2 and 3.

Referring now to Figs. 5 and 6, a similar arrangement of type-bar and toggle is 120

shown, the parts being indicated by similar reference numerals with the exponent *a*. In this exemplification the link 75^a is extended and provided with an articulation 85 to a stationary part of the machine. The fulcrum 62^a of the key-lever is placed in rear of the link 75^a. The articulation 76^a between the link 75^a and the key-lever is a sliding articulation formed by the pivot pin thereof and a slot 86. The articulation of said link with the toggle is a sliding articulation formed by the pivot pin of said articulation and a slot 87. These sliding articulations permit shifting movements of the key-lever and the toggle respectively lengthwise of the link 75^a.

The principle of operation is the same as that explained with reference to the diagram of Fig. 1 and the embodiments of Figs. 2 to 4 inclusive.

Referring now to Figs. 7 and 8, the parts of the machine, the type-bar, the toggle and the key-lever, are similar to the similar parts shown in Figs. 2 and 3, and indicated by similar reference numerals with the exponent *b*. In this exemplification the link 69^b is provided with a slot 91, movable lengthwise of the pivot 73^b. The link 75^b is extended by means of an extension 92, which is provided with a cam 93 engaging a pin 94 stationarily positioned with relation to the frame. When now the key-lever is depressed, the cam rides on the pin and swings the link 75^b as a lever for moving the type-bar toward the roller with a continuously accelerating movement which gathers momentum and force throughout the printing stroke of the type-bar the form of the cam, especially the final portion 90, being such as to impart a final quick impetus to the printing stroke of the type-bar.

Return of the type-carrier is effected with an initially rapid movement, all as explained with reference to the diagram of Fig. 1 and the embodiments shown in Figs. 2 to 6 inclusive.

Referring to Fig. 9, the frame, roller, ribbon, type-bar, guides therefor, and the key-lever, are similar to the similar parts shown in Figs. 2 and 3, and are designated by similar reference numerals provided with the exponent *c*. In this exemplification there is a bell-crank lever 101 having a stationary pivot 102, and sliding articulation with the type-bar comprising a pin 103 and a slot 104. The bell-crank lever further has sliding articulation with the key-lever, comprising a pin 106 and a slot 107.

The bell-crank lever is so shaped that its arms extend at an acute angle to each other, the arm 108 thereof being longer than the arm 109, and extended in such directions and having such connections with the type-bar and the key-lever respectively as to impart a continuously accelerating movement

to the type-bar in its printing stroke for effecting a sharp blow of the type upon the ribbon, which is the resultant of the gathered impetus acquired by the type-bar in its continued positively increasingly accelerated printing stroke, the type-bar moving at highest speed and with greatest force at the moment it strikes the ribbon and perfects its printing stroke.

Initial return movement is effected with a primarily rapid movement to quickly clear the printing space at the tympan roller 52^c for the reception of the type-bar which is next actuated.

Referring to Figs. 10 and 11, the frame, roller, type-bar and key-lever, are similar to the similar parts shown in Fig. 2 and are indicated by similar reference numerals provided with the exponent *d*. In this embodiment of my invention there is a lever 111, which has a pivot 112 stationary on the frame. It has a sliding articulation 113 with the type-bar and a sliding articulation 114 with the key-lever. The articulation 113 comprises an articulating pin on the type-bar and a slot 115 in the lever. This articulation is preferably with a tail-piece 116 of the type-bar. The lever 111 moves in a slot 117 in the plate 67^d. The sliding articulation 114 comprises the articulating pin on the key-lever and a cam-slot 118.

When the key-lever is depressed, the pin of the sliding articulation 114 travels down the wall of the cam-slot 118, the form of the slot being such as to impart a continuously accelerating movement to the type-bar throughout its printing stroke, and the final portion 119 of the cam of the slot imparting a final additionally accelerated printing impulse to the type-carrier, the type-bar gathering momentum and inertia of motion throughout such travel so that it has acquired its greatest impetus and force at the moment the type strikes the ribbon, for effecting a clear impression.

Initial return movement is effected with a primarily rapid movement to quickly clear the printing space at the tympan roller 52^d for the reception of the type-bar which is next actuated.

Referring to Fig. 12, the various parts are similar to the parts shown and described with reference to Figs. 10 and 11, the parts being designated by similar reference numerals provided with the exponent *e*. In the embodiment of my invention shown in Fig. 12, there is an articulation 121 between the key-lever and the lever 111^e, and there is a sliding articulation 122 between the lever 111^e and the frame of the machine, that is to say, this articulation is a stationarily positioned articulation.

It comprises a stationary pivot-pin of the articulation on the frame and a cam-slot 123

in the lever 111^e, provided with a final portion 124, so related that upon depression of the key-lever a continuously accelerating stroke is imparted to the type-bar for accumulating momentum and inertia in the type-bar, and effecting increasing speed throughout the printing stroke of the type-bar, and a final additional acceleration, so that the printing blow is struck when the type-bar is traveling at its greatest speed and with its greatest force. In this exemplification the sliding articulation 122 is located above the key-lever.

Initial return movement is effected with rapid movement as explained with reference to Figs. 10 and 11.

Referring to the embodiment of my invention, shown in Fig. 13, parts similar to those shown in Fig. 12 are shown, and provided with similar reference numerals having exponent *f*. In this embodiment the sliding articulation 122^f is located below the key-lever, the form of the cam-slot, especially the final portion 135 thereof, being such as to impart a continuously accelerating motion to the type-bar and a final blow in its printing stroke similar to the motion described with reference to Fig. 12, so that the type-bar will have its maximum impetus and force applied thereto at the moment its type strikes the ribbon and completes its printing stroke.

Initial return movement is effected with rapid movement as explained with reference to Figs. 10, 11 and 12.

It will be noted that in my improved device the operating means between the key-lever and the type-bar are located below the path of the type-bar, whereby compactness is obtained and that few parts of simple construction are employed.

It will be further noted that by means of my improved device, providing for continuously accelerating movement in the printing stroke, and especially the final additional ac-

celeration of the type-carrier in its printing stroke and the initial quick movement of the following type-carrier in its return stroke, the two movements may take place substantially simultaneously, thereby permitting speed in the operation of the type-writer.

Having thus fully described my invention, what I claim as new, and desire to secure by Letters Patent, is:

1. In a typewriting machine, a frame, a plurality of key levers mounted on a common pivot, a plurality of reciprocating type blocks, a guide for said type blocks mounted above said key levers and substantially parallel thereto, an interconnecting lever on each of said key levers pivoted thereon having one end slidably connected to its type block to actuate the type block in accelerated and correspondingly decelerated movement as it reciprocates and means mounted on the frame engaging with a cam portion on said interconnecting lever for imparting the reciprocating movement to said interconnecting lever as it is carried vertically by its corresponding lever upon which it pivots. 70

2. In a typewriting machine, the combination with a frame, a platen mounted thereon, a horizontally disposed type element adapted for longitudinal movement towards and away from the platen, a key lever pivoted to the frame to swing about a horizontal axis, a lever having its lower end pivoted to the frame and normally disposed at an oblique angle with respect to the horizontal, the upper end of the lever being directly operatively connected with the rear end of the type element, a laterally extending pin carried by the key lever intermediate its ends, which slidably and pivotally engage the lever at a point adjacent the pivotal connection between the lever and frame. 85

In testimony whereof, I have hereunto signed my name.

CHARLES U. CARPENTER.
